(57) CLAIM

The ornamental design for a golf ball, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of a golf ball showing my new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view of a golf ball showing a second embodiment of my new design;

FIG. 8 is a front elevational view of a golf ball showing a third embodiment of my new design;

FIG. 9 is a front elevational view of a golf ball showing a fourth embodiment of my new design; and,

FIG. 10 is a front elevational view of a golf ball showing a fifth embodiment of my new design.

The broken line showing of golf ball dimples is for illustrative purposes only and forms no part of the claimed design.
